UNITED STATES PATENT OFFICE.

WILLIAM B. UPDEGRAFF, OF ELIZABETH, NEW JERSEY.

METAL-WORKING DIE BLOCK.

Application filed October 22, 1924. Serial No. 745,101.

My invention relates to means for forming tubular bodies of metal, of desired and determined transverse section, from metal usually in a semi-fluid condition, under pressure in a container, by extruding it therefrom, through an annular orifice.

The object of my invention is to provide a die block and its accessories, for application in the practice of the method of manufacture above recited, which shall be desirably adaptable in the formation of tubing or rods, or covering for cable, hose, wire, etc., and which, in construction, may be accurately machined to the proper form and relation of the constituent members, at a substantial reduction of time and labor, and, in operation, will ensure the rendition of a product which will be of uniform character, as to proper strength, and desired dimensions.

The improvement claimed is hereinafter fully set forth.

In the accompanying drawings: Figure 1 is a vertical section through a die block illustrating an embodiment of my invention, on the line 1—1 of Fig. 2; Fig. 2, a similar section, taken at a right angle to Fig. 1, the right hand half being on the line 2—2, and the left hand half on the line 2'—2' thereof; Fig. 3, a similar section, on the line 3—3 of Fig. 1; Fig. 4, a view, in perspective, of a choke ring; Fig. 5, a similar view of a guiding sleeve; Fig. 6, a side view, in elevation, of the same; Fig. 7, a vertical section, on the line 7—7 of Fig. 8, through a die block, illustrating means for enclosing a cable in a metallic casing; Fig. 8, a similar section, taken at a right angle to Fig. 7, on the line 8—8 thereof; and, Fig. 9, a view, partly in side elevation, and partly in longitudinal central section, of a nipple applicable in the coating of hose with lead.

In the practice of my invention, referring descriptively to the specific embodiment thereof which is herein exemplified, and first to Figs. 1 to 6 inclusive, the body of the die block is of substantially rectangular section, both longitudinally and transversely, and, is preferably, as shown, made in two parts, an upper section, 1, and a lower section 1^a, which are tongued and grooved, respectively, on their abutting faces, and in use, are firmly secured together, and constitute a containing and strengthening member which maintains the several accessory ele-

ments in their normal positions and relation. The die block may, if desired, be made in a single piece, and when in operative position, is confined between a container, A, charged with a supply of lead or other metal, under pressure, usually in a semi-fluid condition, and abutting against the top of the upper section, 1, and a suitable fixed bearing member, B, against which the lower section, 1^a, abuts. The container, A, is open at its bottom, to a recess, 1^b, in the top of the upper section.

When connected as a unit, for the purpose, the die block sections, 1, and 1^a, are bored out longitudinally, for the reception of accessory members, which will now be described. The ends of the bore of the die block sections, are, when the parts are assembled for operation, closed by front and rear tubular adjustment screws, 3 and 3^a, each having an outwardly tapering bore, and being screwed into the die block, sections. A tubular core or nipple holder, 4, is fitted in the bore of the die block sections, the bore of said core communicating with, and being of substantially the same diameter as, the inner ends of the bores of the adjusting screws, 3 and 3^a. The end of the core, 4, adjoining the rear adjusting screw, 3^a, has an annular shoulder, 4^a, formed upon it, which is forced and held against washers, 4^b, abutting on the die block sections, by the adjusting screws, 3^a. The periphery of the core, 4, adjoining its opposite end, is inwardly curved, and a nipple, 5, is fitted within it. The periphery of the outer end of the nipple, is curved correspondingly with the curvature of the periphery of the core, and its bore tapers inwardly from a diameter, at its inner end, slightly less than that of the core, to its outer end.

Supply channels, 6, for the passage of metal from the container, A, extend downwardly from the recess, 1^b, in the top of the upper section of the die block, to lower terminals which communicate with passages in a guiding sleeve, 7, fitted between the sections of the die block, around the core, 4. The sleeve, 7, is machined to the form shown in Figs. 5 and 6, so as to present full opening to the supply channels, 6, and provide a continuous guiding channel, 13, around the core, 4, as a passage way which accurately diverts the metal, supplied vertically through the channels, 6, into a horizontal direction of traverse, the metal entirely sur-

rounding the core, 4, and being extruded, by the action of the pressure upon it, through the annular orifice between the nipple, 5, and an adjoining die, 10, to be presently described. As shown in Figs. 5 and 6, the channel, 13, is formed in the sleeve, 7, by peripheral recesses, 7^b, located on opposite sides of the middle top portion, 7^c, of its shell, the bottoms of said recesses being curved towards the nipple, 5, from the portion, 7^c, of the sleeve, to the end thereof, nearer the nipple.

The sleeve, 7, accurately fits in the die block sections, 1 and 1^a, and a collar, 7^a, on the sleeve, holds it in position longitudinally therein, and receives the end thrust, resultant upon internal pressure of metal in the die block. The core, 4, is truly cylindrical, from the collar, 4^a, at one end, to its inwardly curved portion at its opposite end, within which the nipple, 5, is fitted, and fits accurately in the sleeve, 7. A die holder, 8, is held in floating position in a machined bore of the die block, at the end thereof at which the front adjustment screw, 3, is located, and is supported and held in position by four lateral adjustment wedges, 9, each of which is actuated by a screw, 9^a, with heads, 9^b. A die, 10, is fitted accurately in the die holder, 8, which, in turn, is fitted to a sealing ring, 11, said ring fitting accurately in a cylindrical portion of a choke ring, 12, of very high grade steel, which is accurately fitted in the die block sections, 1 and 1^a. The sealing ring, 11, fits against the face of the die holder, 8. By suitable movements of the wedges, 9, the die holder may be adjusted relatively to the sealing ring and nipple.

The form of the choke ring, 12, is clearly shown in Fig. 4, by reference to which it will be seen that it is bored, cylindrically at, and for a portion of its length adjoining its end in which the sealing ring 11, as indicated by the reference symbol, 12^a, and that an inwardly projecting ridge or rib, 12^b, extends partially around the upper portion of its bore. The portion of its bore below the ridge, 12^b, is enlarged by a segmental recess, 12^c, as shown in Fig. 4, and indicated in Figs. 1 and 2, the result of which construction is to cause the annular orifice, 13, between the curved portion of the core, 4, at the end thereof, in which the nipple, 5, is fitted, and the surrounding choke ring, 12, through which orifice the metal is extruded, to be of different widths, in different portions of its extent. Rotation of the core, 4, sleeve, 7, and choke ring, 12, in the die block, is prevented by dowel pins, fixed in the lower die block section, and engaging these members, in the ordinary manner.

The choke ring, 12, which is an important feature of my invention, acts as a strength-

ening cylinder, to resist the bursting pressure induced by the high unit metal pressure, and thus to relieve, to a large extent, the tendency of the sections of the die block to be separated by said pressure, and its further function, in connection with the sealing ring, is to prevent the access of metal to the annular space surrounding the die holder, 8, which space must be provided to permit the lateral adjustment thereof. The degree of opening between the choke ring and the core, at any particular portion of the intervening orifice, 13, is regulated in accordance with the requirements of extrusion at such particular portion, that is to say, the orifice is caused to be of greater width, at points where the metal flows less readily, and of lesser width where it flows more readily. The exact degree of the opening, at any one point, is determined by trial in actual service. Slight variations of the orifice may be made by varying the position of the core, by slackening the rear adjustment screw, 3^a, and inserting additional washers, 4^b, or by removing one or more of said washers and tightening up the adjustment screw, 3^a. The adjustment screws are so regulated as to cause the flow of metal through the orifice of extrusion, to be practically uniform at all parts thereof, thereby ensuring the formation of pipe of uniform wall thickness. The slackening of the front adjustment screw, 3, effects a wider opening and consequent increased thickness of the wall of the pipe, and the tightening of said screw, provides a narrower opening and a resultant thinner wall in the pipe produced.

Alterations in the specific form and dimension of the core, 4, the sleeve, 7, the choke ring, 12, and the sealing ring, 11, may obviously be made, without departure from the spirit and operative principle of my invention, and thereby the passage for the extrusion of metal, can be varied within wide limits, to produce any desired distribution of metal, and manufacture pipes, either of uniform circular section, or of such variations therefrom as may be desired. In such variations of form and dimensions, the following main features of the operative die block structure, i. e., the die block sections, 1^a and 1, die holder, 8; and adjustment screws, 3 and 3^a, are not altered in any particular, although the passage ways for metal may be radically varied, by the application of different specific forms of the sleeve, the core, the choke ring, and the sealing ring, with suitably formed nipples and dies.

Figs. 7 to 9 inclusive, illustrate the application of my invention in covering wires, cables or hose, with a casing of lead pipe. In the instance exemplified, two wires or cables, 14, are fed, side by side, into the die block, through the bores of the rear adjustment screw, 3^a, and the nipple, 5, and are

covered by a casing, 14^a, of lead pipe, which is extruded around them, through an annular orifice, as in the structure previously described. In cases where it is desired that the casing shall be interiorly corrugated, this may be effected by the use of a nipple, 5, having corrugations, 5^a, on its face, as shown in Fig. 9.

In die block designs of the prior art, in which metal is extruded through an annular orifice, it has been necessary to work out, from solid forgings or castings, carefully and laboriously, and mainly by hand tools, the channels for the passage of metal from the top opening in the container, to the annular orifice for the extrusion of the metal, between the nipple and the die. This has heretofore been a very difficult and expensive operation, as the openings had to be made in forgings comprising the upper and lower sections of the die block. Incorrect machine work involves the replacement of these large parts, and furthermore, it is almost impossible, in doing work of this character, to ensure accurate duplication of parts, or effect a change in the accessories of a die block of the prior designs, without practically constructing a new block. Again, in the prior designs, it is impossible to readily change from one set of accessories to another, and return to the application of the original accessories.

In the construction provided by my invention, as hereinbefore described, the form of the passage ways for metal can be varied without involving any change in the sections of the die block, and it is readily practicable to machine the parts to standard drawings, and thereby to duplicate existing die block structures, without difficulty and without resorting to cut and try methods. An important feature of my invention is the capacity which it affords, of readily removing the die and nipple, without removing the die block from the press, in connection with which it is operated, and without disturbing the adjustments thereof. By removing the front adjustment screw, the die holder and die can be taken out, permitting the removal of the sealing ring. When this is done, if, in the use of the block, metal has been deposited in the passage ways, the small amount thereof, surrounding the exposed end of the nipple, can be melted out, and the nipple pushed out of the die block by a stick or rod, passed through the bore of the rear adjustment screw. A new nipple and die may then be inserted, and the removed parts replaced, thus rendering it easy to make changes in the size of the die or nipple, or both, when it is desired to produce pipe or casing of a different size.

The ability of readily adjusting the die laterally, relatively to the nipple, while the die block is in use, and without disturbing

any other adjustments, is especially desirable. Such lateral adjustment is particularly important in covering cable, where uniformity of lead wall thickness is essential.

It is likewise possible to remove the rear adjustment screw, and draw out the core, through the opening thereby presented, and to replace the core, or insert another of the same outside diameter, but differing in detail, such as being of greater or smaller bore, without removing the die block from the press or disturbing the press adjustment. This capability is of special advantage in die blocks used in the manufacture of lead pipe of comparatively large diameter, or for covering large cable or hose, as it is necessary to reduce the bore of the core, to correspond with a comparatively large reduction in the bore of the nipple. This necessity arises from the fact that the intense pressure of the lead, exerted against the face of the nipple, makes necessary a bearing area between the nipple and the core, sufficient to safely withstand such pressure. The die holder may be replaced by another, having a larger or a smaller bore, and it is therefore possible to maintain, by suitable die holders, sufficient bearing area between the die holder and the die.

There results, from the ability of changing cores and die holders, which is presented by my invention, the capacity of forming a much greater range of sizes of lead pipe, in one die block, than would be practicable if the interchangeability of cores and die holders could not be readily effected.

I claim as my invention and desire to secure by Letters Patent:

1. In a metal working die block, the combination of a body, having a supply channel for the passage of metal; a die holder, fitted therein, a die, fitted in said die holder; a core, fitted in the body, in line with the die holder; a nipple, fitted in the core, and separated from the die by an annular space, communicating with the supply channel; a sleeve, governing the flow of metal through the die block; and an adjustment screw, engaging the die block and bearing on the die holder.

2. In a metal working die block, the combination of a body, having a supply channel for the passage of metal; a die holder, fitted therein; a die, fitted in said die holder; a core, fitted in the body, in line with the die holder; a nipple, fitted in the core, and separated from the die by an annular space communicating with the supply channel; and adjustment screws, engaging the die block, and bearing on, without rotative connection with, the die holder and the core, respectively.

3. In a metal working die block, the combination of a body, having a supply channel for the passage of metal; a die holder,

- fitted in the body; a die, fitted in the die holder; a core, fitted in the body; a nipple, fitted in the core; and means for effecting longitudinal adjustment of the core, towards or from the die holder without variation of the relation of said members to a common middle plane.
4. In a metal working die block, the combination of a body, having a supply channel for the passage of metal; a die holder, fitted in the body; a die, fitted in the die holder; a core, fitted in the body; a nipple fitted in the core; and means for adjusting the die holder, relatively to the core without variation of the relation of said members to a common middle plane.
5. In a metal working die block, the combination of a body, having a supply channel for the passage of metal; a die and a nipple, supported, in line, in the body, and spaced apart longitudinally; and a choke ring, surrounding the end portion of the nipple, and spaced apart therefrom.
6. In a metal working die block, the combination of a body, having a supply channel for the passage of metal; a die holder, fitted in the body; a die, fitted in the die holder; a sealing ring, fitting against the face of the die holder; a nipple, fitted in the body; and a choke ring, fitting around the nipple.
7. In a metal working die block, the combination of a body, having a supply channel for the passage of metal; a die holder, fitted in the body; a die, fitted in the die holder; a sealing ring, fitting against the face of the die holder; a core, fitted in the body; a nipple, fitted in the core; and a choke ring, fitting around the core, and spaced apart therefrom.
8. In a metal working die block, the combination of a body, having a supply channel for the passage of metal; a die, fitted in the body; a sealing ring, fitting against the face of the die; a core, fitted in the body; a nipple, fitted in the core; and a choke ring, fitting around the adjacent end portion of the core; said choke ring having a portion of its bore, adjacent to the core, recessed eccentrically thereto.
9. In a metal working die block, the combination of a body, having a supply channel for the passage of metal; a die, fitted in the body; a sealing ring, fitting against the face of the die; a core, fitted in the body; and a choke ring, fitting around the sealing ring, and surrounding, and spaced apart from, the adjacent end portion of the core; said choke ring having a portion of its bore, adjacent to the core, eccentric thereto.
10. In a metal working die block, the combination of a body, having a supply channel for the passage of metal; a tubular core and a tubular die holder, supported removably in the body, and separated, longitudinally, by a space communicating with the bores of the core and the die holder; a guiding ring, surrounding the core, and having a peripheral recess, establishing communication between the supply channel and the space between the core and the die holder; a choke ring, surrounding said space and having a portion of its bore, adjacent to the core, recessed eccentrically thereto; and tubular adjustment screws, engaging opposite ends of the body, the bores of said screws communicating with the bores of the core and of the die holder, respectively.
11. A guiding ring for a metal working die block, which is in the form of a sleeve, adapted to fit in the die block, and having one of its ends so shaped as to direct the flow of metal through the die block.
12. A guiding ring for a metal working die block, which is in the form of a sleeve, adapted to fit in the die block, and having one of its ends so shaped as to direct the flow of metal through the die block, and a portion of which is flanged for engagement with the die block.
13. A choke ring for metal working die blocks, having a body, the bore of which is partly eccentric to its axial line.
14. A choke ring for metal working die blocks, having a body, the bore of which is recessed outwardly from its axial line, on one side thereof, for a portion of its length, and which has an inward swell or projection opposite its recessed portion.

WILLIAM B. UPDEGRAFF.
